COOLER FOR OIL AND OTHER LIQUIDS

James Frank Belaieff and Cyril Terence Delaney,
Cricklewood, London, EnglandApplication September 18, 1939, Serial No. 295,544
In Great Britain February 15, 1939

7 Claims. (Cl. 257-2)

This invention relates to a new or improved type of cooler for liquids, such as oil, whose viscosity varies appreciably at different temperatures.

- 5 The present invention consists in the combination of two radiators arranged in V-shape formation and containing radiator tubes of small gauge, a radiator within the V section and containing radiator tubes of large gauge, a conduit 10 at each side of the radiators which are arranged V-shape and form a closure therefor, and two header tanks and an intermediate tank connected with the two radiators arranged V-shape.
- 15 Referring to the accompanying drawing:

Fig. 1 is a sectional view taken on line 1—1 of Fig. 3.

Fig. 2 is a horizontal section on approximately the line 2—2 of Fig. 1.

Fig. 3 is a sectional view of Fig. 1 looking in the direction of the arrow, and

Fig. 4 is an end elevation of the structure shown in Fig. 1 looking from right to left in said figure.

Throughout the views similar parts are marked 25 with corresponding letters of reference.

In carrying this invention into effect two radiators *a*, *b*, are arranged in V-shaped formation as shown in Fig. 1. These two radiators have very small gauge of tubes *c*. Within the centre 30 of the V-shape formation of radiators is mounted another radiator with horizontally arranged tubes *d* of larger gauge to those at *c*. Air ducts are provided from an entrance *e*, through the gills of the radiators *a*, *b*, to the outlets *f*, *g*, as shown in Fig. 1. Header tanks for the radiators *a*, *b*, are shown at *h*, *i*, and an intermediate tank for the purpose hereinafter described is shown 35 at *j*.

Referring specially to Figs. 2, 3, 4, it will be 40 seen that there are conduits *k*, *l*, on each side of the radiators *a*, *b* and form a closure therebetween.

The operation of the cooler is as follows:

Oil enters the tubes *d*, through an opening *m*, 45 passes through the tubes *d* from the conduit *k* to the conduit *l*. The conduits *k* and *l* serve as headers for the tubes *d*. The oil then passes down the conduit *l* into the lower header tank *i*, as indicated by the arrows in Fig. 3. The oil 50 then passes up the lower small tubes *c* of the lower radiator *b* into the intermediate tank *j* and then up the small tubes *c* of the upper header tank *h* and out of the opening *n*.

When the oil is too viscous for passing through 55 all the abovementioned stages of transit, it enters

the opening *m*, passes through the larger tubes *d* into the conduit *l* and then direct from this conduit *l* into the upper header tank *h* instead of the lower header tank *i*. This direct operation is provided for by the by-pass valve *o* which is of any known and convenient construction, such as the spring controlled ball type of valve as indicated in Fig. 3.

I claim:

1. In a heat exchanger, the combination of two radiators arranged in V-formation, said radiators each including tubes and headers, and connected together in series, a third radiator comprising side headers and connecting tubes with the tubes passing between the first two radiators and within the V thereof, means to admit liquid into one of the headers of the third radiator, means to pass the liquid from the other header of the third radiator into an end header of one of the first two radiators, means to discharge the liquid from the end header of the other of the first two radiators and means to conduct air over the tubes of the third radiator from the entrance of the V, and pass same through between the tubes of the first two radiators.

2. In a heat exchanger, the combination of two radiators arranged in V-formation, said radiators each including tubes and headers, and connected together in series, a third radiator comprising side headers and connecting tubes with the tubes passing between the first two radiators and within the V thereof, means to admit liquid into one of the headers of the third radiator, means to pass the liquid from the other header of the third radiator into an end header of one of the first two radiators, means to discharge the liquid from the end header of the other of the first two radiators and means to conduct air over the tubes of the third radiator from the entrance of the V, and pass same through between the tubes of the first two radiators, there being a direct passage from said other header of said third radiator to the end header of said other of the first two radiators, and a back-check valve in said direct passage.

3. In a heat exchanger, the combination of two radiators arranged in V-formation, said radiators each including tubes and headers, and connected together in series, a third radiator comprising side headers and connecting tubes with the tubes passing between the first two radiators and within the "V" thereof, means to admit liquid into one of the headers of the third radiator, means to pass the liquid from the other header of the third radiator into an end header

- of one of the first two radiators, means to discharge the liquid from the end header of the other of the first two radiators and means to conduct air over the tubes of the third radiator
5 from the entrance of the V, and pass same through between the tubes of the first two radiators, there being a direct passage from said other header of said third radiator to the end header of said other of the first two radiators,
10 and a back-check valve in said direct passage, the tubes of said third radiator being of substantially larger gauge than those of said first two radiators.
4. In a liquid cooler, two radiators comprising
15 two sets of liquid conveying tubes, an end header for each set of tubes at one end and a common header for the other ends of said sets of tubes, said headers being horizontally disposed and the sets of tubes being inclined respectively upward-
20 ly and downwardly from the common header, by virtue of which the two radiators are arranged in V-formation, means to discharge liquid from the one end header, a third radiator comprising side headers and cross tubes connecting the
25 same, the cross tubes lying in horizontal rows between the first two radiators and in the V thereof, means to admit liquid into one side header, means for passing the liquid from the other side header into the other end header, and an air
30 duct cooperating with said radiators to receive air in the V, pass the air over the tubes of the third radiator and then through the spaces between the tubes of the first two radiators.
5. In a liquid cooler, two radiators comprising
35 two sets of liquid conveying tubes, an end header for each set of tubes at one end and a common header for the other ends of said sets of tubes, said headers being horizontally disposed and the sets of tubes being inclined re-
40 spectively upwardly and downwardly from the common header, by virtue of which the two radiators are arranged in V-formation, means to discharge liquid from the one end header, a third radiator comprising side headers and cross tubes
45 connecting the same, the cross tubes lying in horizontal rows between the first two radiators and in the V thereof, means to admit liquid into one side header, means for passing the liquid from the other side header into the other end header, and an air duct cooperating with said radiators to receive air in the V, pass the air over the tubes of the third radiator and then through the spaces
50 between the tubes of the first two radiators, and a back-check valve controlled by-pass duct from said other side header to the end header from which the liquid is discharged.

the spaces between the tubes of the first two radiators, and a back-check valve controlled by-pass duct from said other side header to the end header from which the liquid is discharged.

6. In a liquid cooler, two radiators comprising 5 two sets of liquid conveying tubes, an end header for each set of tubes at one end and a common header for the other ends of said sets of tubes, said headers being horizontally disposed and the sets of tubes being inclined respectively upward- 10 ly and downwardly from the common header, by virtue of which the two radiators are arranged in V-formation, means to discharge liquid from the one end header, a third radiator comprising side 15 headers and cross tubes connecting the same, the cross tubes lying in horizontal rows, with the tubes of a row in contact side-by-side, between the first two radiators and in the V thereof, means to admit liquid into one side header, means for passing the liquid from the other side header into the other end header, and an air duct co- 20 operating with said radiators to receive air in the V, pass the air over the tubes of the third radiator and then through the spaces between the tubes of the first two radiators. 25

7. In a liquid cooler, two radiators comprising two sets of liquid conveying tubes, an end header for each set of tubes at one end and a common header for the other ends of said sets of tubes, said headers being horizontally disposed and the sets of tubes being inclined respectively upward- 30 ly and downwardly from the common header, by virtue of which the two radiators are arranged in V-formation, means to discharge liquid from the one end header, a third radiator comprising side 35 headers and cross tubes connecting the same, the cross tubes lying in horizontal rows, with the tubes of a row in contact side-by-side, between the first two radiators and in the V thereof, means to admit liquid into one side header, means for passing the liquid from the other side header into the other end header, and an air duct co- 40 operating with said radiators to receive air in the V, pass the air over the tubes of the third radiator and then through the spaces between the tubes of the first two radiators, and a back-check valve controlled by-pass duct from 45 said other side header to the end header from which the liquid is discharged. 50
